Inventor:
Harry U. Marsh

UNITED STATES PATENT OFFICE

HARRY V. MARSH, OF CHICAGO, ILLINOIS

EASEL

Application filed February 21, 1931. Serial No. 517,440.

The present invention relates to an easel, and has particularly to do with a type of advertising device known in the trade as a "blow-up" easel. The device comprises a 5 poster or advertising sheet, reinforcing members at the top and bottom thereof, and an easel for stretching such sheet and engaging said reinforcing members for attachment to the sheet.

10 It is manifest that a thin sheet of paper, highly calendered or otherwise treated, is more suitable for advertising reproductions than heavy cardboard, both from a printing point of view and from the point of view of economy.

Such a sheet has the additional advantage of being collapsible and thus possesses the capacity for being packed in a small space. When spread, it does not show creases or 20 breaks, as a cardboard sheet would. When such a flexible sheet is provided with a compact, foldable or collapsible easel, then the easel and the poster sheet may be wrapped together or separately in detached form and 25 disposed in the average carton of merchandise for ready shipment with the merchandise to which it relates. Such an arrangement is superior to separate shipment for merchandise and advertising material in that it 30 assures that selected advertising material will reach a retailer concurrently with the goods covered by the advertisement. When separate packages for merchandise and advertising material are employed, the merchandise 35 invariably arrives at one time and the advertising either in advance of the merchandise or after, with the conventional result that there is no suggested cooperation by intimate association between the two to 40 sell the goods.

An object of the present invention is to provide a new and novel easel structure. A second object of the invention is to supply an improved blow-up easel. A third object 45 of the invention is to obtain an improved supporting member for a flexible sheet.

These objects, and such other objects as may hereinafter appear, are obtained by the novel construction, unique arrangement, and improved combination of the several elements 50

illustrated in the accompanying drawing in which two forms of the invention are disclosed.

In said drawing:—

Figure 1 is a rear view of one form of the 55 invention;

Figure 2 is a side view thereof;

Figure 3 is a plan view of the second form 60 of the invention;

Figure 4 is a side view of such second form 65 of the invention; and

Figure 5 is an illustration showing a poster sheet like that shown in the previous illustrations rolled up and an easel collapsed, the 70 two being in package form for shipment.

Like reference characters are used to designate similar parts in the drawing and in the description of the invention which follows.

Reference should be had first to Figures 1 and 2. In said figures, the numeral 10 indicates a poster sheet which may be of thin material and which is generally incapable of self-sustenance. Said sheet 10 has at its top a reinforcing strip 11 and at its bottom a second reinforcing strip 12 which strips are of heavier material, generally strips, and which ordinarily reach from vertical edge to vertical edge of the poster sheet 10. Adhesive may be employed between the sheet 10 and the strips 11 and 12 to secure the latter in position. 75 Display matter or advertising material, which may be lithographed, printed or otherwise reproduced, is generally upon the face of the sheet 10 and is not here shown.

In the strip 11 is a rivet 13 or other anchoring means and in the strip 12 is a rivet 14. Said rivets 13 and 14 provide a useful means for attaching to the sheet 10 at its reinforced sections 11 and 12 an easel or supporting member to maintain the sheet 10 spread into a flat 80 plane and in substantially upright position.

Other fastening means could be substituted for the rivets.

In Figures 3 and 4, the sheet 10 is the same as in Figures 1 and 2, but the form of easel 95 illustrated in Figures 3 and 4 is different and distinct from the easel shown in Figures 1 and 2. The easel shown in Figures 1 and 2 comprises several narrow strips joined together. Referring to Figure 2, it will be noted 100

that the easel comprises an upper strip 15. Next thereto, generally, is a strip 16 of similar width and of like material. Each of said strips 15 and 16 is supplied with an aperture which may be of the keyhole type. The aperture in strip 15 is designated 17 and that in strip 16 is designated 18. By said apertures, strips 15 and 16 are attached to the reinforcing members 11 and 12 to separate said strips 11 and 12 and thereby spread the sheet 10.

A third strip 19 may be attached over a part of the length to the strip 16, the attaching means comprising in part a rivet adjacent one end later to be mentioned and a metallic stitch or staple 20. A fourth strip 21 completes the assembly as illustrated.

Through the strips 15, 16, 19 and 21 is a rivet 22, previously mentioned which forms one of the attachment means between strip 19 and strip 16, and which further provides a joinder between the four strips, permitting of the strip 15 being rotated with said rivet 22 as an axis to be moved arcuately from contact over its full length upon the strip 16 to 25 a longitudinal extension of said strip 15 as is shown in Figure 2.

Strip 21 includes a leg 22 through which there is a dovetail slot 23 to interlock therein. The parts 21 and 22 may be separated for 30 ready articulation by a score 26 and the parts 19 and 24 may be similarly separated by a score 27. Generally the staple 20 is adjacent to the score 27.

When in packaged condition, the strip 15 35 rests its whole length upon the strip 16, and the strip 19-24 rests flat against the strip 16. The strip 21-22 rests against the strip 19-24. Thus a short compact package of less length than the height of the extended sheet 10 is had. The easel may be rolled up with the sheet 10 or it may be attached to the outside of a rolled up sheet 10. In either condition the two may be readily secured together by an elastic band 28.

45 When the easel is to be used, the strip 15 is rotated or moved from the position shown in Figure 5 to the position shown in Figure 2. The strip 21-22 is then articulated on the score 26, and the strip 19-24 is articulated upon the score 27. Next the tongue 25 is inserted through the dovetail slot 23 to provide an interlock between the members 21-22 and 19-24. The strips 15 and 16 are attached to the sheet 10 by inserting the rivet 13 through 50 the slot 17 in member 11 and the rivet 14 through the slot 18 in member 12. In such assembly, the device is in condition for use with the sheet 10 spread into a flat horizontal plane, and in condition to be held upright by the easel.

If preferred, the strips 15 and 16 may be made in a continuous piece which, of course, reduces the compactness of the easel when not in use. It is perfectly manifest, too, that the strip 19-24 and the strip 21-22 may be made

in a single piece, folded upon itself above the rivet 22.

In the form of the invention shown in Figures 3 and 4, a similar sheet 10 with reinforcing strips 11 and 12 and rivets 13 and 14 is employed. A strip 30 having a slot 33 forms the upper member of the easel as illustrated in Figures 3 and 4. A strip 32 having a slot 33 forms a lower member of the easel for attachment to sheet 10 when the strips 30 and 32 are extended. Through the strip 30 is a slot 34 which may be of dovetail configuration, if desired. Extending from the strip 32 is a tongue 35, separated therefrom by a score 36. Tongue 35 may be shaped to provide a secure interlock with strip 30, as for example, it may be dovetail in configuration.

The third member in the easel as illustrated comprises a strip 37 having two extensions 38 and 39. The extension 38 has a dovetail tongue 40 extending from the free end thereof and the extension 39 has a dovetail slot 41 through which the tongue 40 may be inserted for interlocking purposes.

Between the strips 37, 32 and 30 is a rivet 42. The strip 37 is additionally attached to the strip 32 by a staple or rivet 43.

The easel illustrated in Figures 3 and 4 is adapted to be folded by moving the strip 30 about the rivet 42 relatively to the strip 32 so that the strips 30 and 32 are made to lie together. The strip 37 has its extension 38 flat against the strip 32, while the extension 39 is made to lie flat against the strip 37 and the strip 38. When in such take down position, the easel may be rolled up with a poster sheet 10 as is shown in Figure 5 and the two items secured together by an elastic band or a cord 28.

In extended position, the easel shown in Figures 3 and 4 is attained by rotating the strip 30 relatively to the strip 32, articulating the strip 32 so that the extension 35 may be inserted through the slot 34 in strip 30 to prevent displacement of the strips 30 and 32 from alignment. The articulation obtained at score 36 facilitates insertion of the tongue 35 through the slot 34.

To complete the assembly of the easel, the extension 39 is articulated upon score 44 to the position shown in Figure 4. The strip 39 is then articulated at score 45 to the position shown in Figure 4, the tongue 41 being inserted through the slot 40 to provide an interlock between the sections 38 and 39.

The easel is then attached to poster sheet 10 by causing the engagement of the rivet 13 with the keyhole slot 31 and the rivet 14 with the keyhole slot 33.

In the form of the invention shown in Figures 3 and 4, there are but three thicknesses of material in the easel. If it is desired to reduce the strips to two, an inte-

gral spreader strip may be employed, the strips 30 and 32 then being in continuity.

Other forms of the invention are possible, the scope of the invention being defined by 5 the claims appended hereto.

I claim:

1. An easel for use with a blow-up sheet or poster sheet comprising a plurality of narrow strips two of which are pivotally connected to one another, said two strips being relatively movable to provide a spreader for said poster sheet, one of the remaining strips providing a leg for said spreader strips when extended, and the other a means for holding 10 said leg at an angle to said extended spreader strips there being a fastening means common to all four strips.
2. An easel for use with a blow-up sheet or poster sheet comprising a plurality of narrow strips two of which are pivotally connected to one another, said two strips being relatively movable to provide a spreader for said poster sheet, one of the remaining strips providing a leg for said spreader strips when 15 extended, and the other a means for holding said leg at an angle to said extended spreader strips, there being a fastening means common to all of said strips, and a second fastening means intermediate one of the spreader strips and the leg holding strip whereby said leg forming and leg holding strips are maintained in alignment with one of said spreader strips.
3. An easel for a poster sheet or the like 20 comprising a plurality of strips having connecting means therebetween to facilitate compact packaging when not in use, one of said strips being relatively movable to another of said strips about said connecting means to provide an elongated member adapted to 25 spread a poster sheet with which the easel is used, and means for locking said strips in extended position comprising a slot in one strip and a tongue on the other and insertable 30 through said slot.
4. A new and novel easel for a poster sheet comprising a plurality of strips joined together by a rivet or the like, one of said strips being movable relatively to the other 35 strips and upon said rivet as a pivot whereby an elongated lineal member is provided to support a poster sheet, a third strip adapted to be articulated to provide a leg for the other of two strips, locking means for maintaining 40 said leg forming strip in an extended position, and a fastening means common to said strips and locking means.

HARRY V. MARSH.
